center causing the switch contacts 51 and 55 to open. The passage of fluid under control of the pressure regulating device 15 insures the discharge of the fluid under proper conditions of pressure while the temperature of the fluid at discharge is regulated under control of the operation of the apparatus within conductor 14 as described.

The apparatus of my invention has many applications such as a domestic water heater in lieu of the familiar type of instantaneous gas heater now installed in many homes. My invention also finds application in the heating of air, oil and other fluids where it is necessary to raise the temperature quickly under conditions of high efficiency.

While I have described my invention in connection with a fluid heater it will be understood that the principles of my invention may also be applied to the heating of anything which can be forced through a pipe. The intense heat which is developed in the secondary tubular winding due to the shunt power across the winding, enables heat to be produced instantaneously and enables hot water and steam to be maintained at a desired temperature in a storage tank. The production of steam power by use of the apparatus of my invention provides means for driving engines and developing motive power for automobiles, ships, airplanes and other vehicles.

I have found the apparatus of my invention highly practical in its construction and operation and while I have described my invention in one of its preferred embodiments, I desire that it be understood that modifications may be made and that no limitations upon my invention are intended other than are imposed by the scope of the appended claims.

What I claim as new and desire to secure by Letters Patent of the United States is as follows:

1. In a fluid heater, a housing, an electrical transformer having a core provided with vertical legs supported in said housing, a primary winding coiled about one leg of said core, a fluid pipe of hollow metallic tubing extending into said housing and having a portion formed into a single coil about the other leg of the core in spaced relation thereto intermediate the height of the leg to form a secondary winding inductively related to said primary winding, portions of the

tube adjacent the coil being bridged by conductive material, a cylindrical casing about the second mentioned leg of the core and secondary winding and adjoining portions of said tube, said casing having heads at its upper and lower ends bearing against upper and lower portions of the core, a packing of heat insulation filling said casing and disposed about the secondary winding and between the winding and leg of the core, and temperature controlled means associated with the fluid pipe within the housing for regulating the flow of current through the primary winding.

2. In a fluid heater, a housing, an electrical transformer in said housing having a core provided with spaced legs, a primary winding coil support carried by one leg of said core, a primary winding carried by said support and having exposed surfaces for radiating heat within the housing, a fluid pipe of hollow metallic tubing extending into said housing and having a portion formed into a single coil about the other leg of the core in spaced relation thereto to form a secondary winding, a bridge of conductive material being connected across the ends of said secondary winding, a casing disposed about the second mentioned leg of said core and the secondary winding and adjoining portions of the tubing forming said secondary winding, and a packing of heat insulating material filling said casing and disposed about the secondary winding and between the winding and leg of the core.

3. In a fluid heater, an electrical transformer having a core provided with spaced legs, a primary winding coil support carried by one leg of said core, a primary winding mounted on said support, said support having exposed surfaces for radiating heat from the same, a fluid pipe of hollow metallic tubing having a portion formed into a coil about the other leg of the core in spaced relation thereto to form a secondary winding, a casing individual to the second mentioned leg of said core and the secondary winding and adjoining portions of said tubing, and a packing of heat insulating material filling said casing and disposed about the secondary winding and between the winding and leg of the core.
